CLAIM

The ornamental design for handle base for game controller, as shown and described.

DESCRIPTION

FIG. 1 is bottom perspective view of the handle base for game controller of the invention.

FIG. 2. is a top view thereof.

FIG. 3 is a right side view thereof.

FIG. 4 is a bottom view thereof.

FIG. 5 is a front view thereof; and,

FIG. 6 is a rear view thereof.

The left side view of the handle base for game controller of the invention (not shown), is a mirror image of the right side view shown in FIG. 3. Portions of the controller shown in broken lines form no part of the claimed design.
